Primary Examiner — Selina Sikder(74) *Attorney, Agent, or Firm* — Quarles & Brady, LLP(57) **CLAIM**

The ornamental design for a control console, as shown and described.

DESCRIPTION

FIG. 1 is a top, left, front perspective view of a control console embodying my new design;

FIG. 2 is a top plan view thereof;

FIG. 3 is a front elevational view thereof;

FIG. 4 is a left elevational view thereof;

FIG. 5 is a right elevational view thereof;

FIG. 6 is a rear elevational view thereof; and,

FIG. 7 is a bottom plan view thereof.

The broken line representations in the views are for illustrative purposes only and form no part of the claimed design.
